HOSIERY

John Wyckoff Mettler, East Millstone, N. J., assignor to Interwoven Stocking Company, New Brunswick, N. J., a corporation of New Jersey

Application April 16, 1937, Serial No. 137,215

10 Claims. (Cl. 66—172)

My invention consists in the novel features hereinafter described, reference being had to the accompanying drawings which show several embodiments of my invention selected by me for purposes of illustration, and said invention is fully disclosed in the following description and claims.

In the knitting of hosiery and particularly men's half hose and men's, women's, boys' and children's anklets, it has been customary to knit a top portion, hereinafter referred to as the top, of 1 x 1 rib knitting, which in the case of men's half hose is approximately five inches in length, on a rib knitting machine. This rib top is then transferred to another machine and the last row of stitches of the top placed over the needles thereof and the leg and foot are knit onto the top, most usually by plain knitting. The rib top while usually having the same number of stitches as the plain knit leg is a narrower fabric of greater elasticity than plain knitting and provides the necessary stretch and elasticity to enable the leg portion of the sock or stocking to be drawn over the heel while it will immediately contract upon the leg and provide a form fitting function to hold the top snugly around the leg. The public has long been accustomed to expect, in men's socks particularly, a rib top of this character.

There has recently been developed, a new top for hosiery of this kind which is formed of plain knit or flat fabric, knit on only one set of needles, in which a continuous elastic thread of rubber, or the well known "Lastex" is incorporated in selected, preferably spaced, courses, under tension and locked into the fabric in any desired way at spaced wales of said rubber bearing courses in the process of knitting, the elastic thread being floated on the inner face of the fabric between the points at which it is locked in the fabric. The spaced wales in the several courses are preferably vertically aligned and the tension of the elastic thread draws the top into vertical rib-like ridges, or corrugations, simulating rib fabric, while when the stocking is worn these ridges tend to smooth out more or less, and the circular series of floats form substantially continuous circular beads on the inner face of the fabric, which individually slightly indent or impress the skin of the wearer and as they extend transversely of the direction in which the stocking tends to slip, serve to support the stocking on the leg without the use of a garter, and with such light tension that the wearer is unconscious of it, in actual use. This type of fabric per se,

I will hereafter refer to as rubber incorporated ridged fabric to distinguish it from rib knit fabric.

In the practical manufacture of stockings, socks, or anklets, having such elastic incorporated tops, the elastic thread carrying courses even if separated as widely as every fourth or fifth course, or more, will contain approximately thirty rounds of lastex or other elastic thread, which adds materially to the cost of the sock or stocking.

I have found by experiment that a much smaller number of courses of elastic thread will be ample to enable the top to provide the self-supporting function. If, however, the spaced courses are made fewer in number and distributed at intervals along the length of the top, the plain knit body fabric of the top between such groups of spaced elastic thread bearing courses will balloon outward, producing an unsightly effect in the hand, and depriving the top of the snug elongated form fitting effect for which the top has heretofore been particularly relied on, and to which the purchasing public is accustomed. To concentrate the spaced elastic thread bearing courses, at any part longitudinally of the length of the top leaving the remainder of plain knit courses without the rubber thread, will produce an unsightly effect, particularly if they are concentrated at any point below the extreme upper part of the top, likewise the snug elongated form fitting effect would be lost.

According to my present invention, I form a top for a sock, anklet or stocking, in which I employ a much smaller number of spaced rubber bearing courses, sufficient to fully insure the support of the leg of the stocking, but no more, and at the same time I preserve the form fitting effect of the top throughout the entire length of the top which may be and usually is several times the length of the elastic thread incorporated ridged fabric. This I accomplish by knitting portions of the top of plain knit, or flat elastic thread incorporated ridged fabric, and other portions of rib knit fabric, both of which furnish the desired form fitting effect throughout the entire length of the top, while the floats of elastic thread or Lastex in the elastic thread incorporated ridged fabric perform the self-supporting function. The ridges of the elastic thread incorporated fabric tend to merge into the ribs of the rib fabric so as to present a harmonious appearance and may be practically in uniform alignment if the spaces between the points of interlocking the elastic thread in the ridged fabric are identical with the spaces be-

tween the ribs of the rib fabric, as for example, if the elastic thread is locked into the ridged fabric in every alternate wale and the rib fabric is a 1 x 1 rib. This exact or practically exact alignment is not at all necessary and I prefer to lock the elastic thread in the ridged fabric, at about every fourth wale, and to employ a 1 x 1 rib fabric therewith. Although other combinations may be used, if desired, this has been found in practice the most advantageous.

In carrying out my invention, a great saving of expense is obtained by eliminating so many courses of elastic thread, without any loss of efficiency of the top either as to its self-supporting or form fitting function, and without impairing the sightliness of the sock or stocking, either as displayed or sold over the counter, or on the leg of the wearer. The sections of elastic incorporated ridged plain or flat fabric, and rib fabric, may be variously arranged in the top. For example, the upper part of the top may be formed of the ridged fabric and the lower of rib fabric, or vice versa, or the two kinds of fabric may be divided up and formed as alternating bands with pleasing effect and substantially equal efficiency.

In carrying out my invention, the upper end of the top is provided with a welt or selvage which may be stretched to the same extent as the top and which may be formed in any known or desired manner, and such welt or selvage may or may not have elastic threads incorporated therein as hereinafter described.

The leg and foot of the stocking are preferably knit integrally with the last course of the top which may be either plain knit, or rib knit, and the leg of the stocking may be either plain knit or rib knit, and if rib knit, it may be of the same type as the rib knit portion of the top, 1 x 1, or of a different type as 6 x 3 rib, or any other kind of rib as preferred. While I prefer to knit the top and leg as a continuous integral fabric, the top may be knitted separately and attached to the leg by stitching, looping, or in any other desired manner.

My invention can be carried out by hand, or by means of the well known Komet Knitting Machine, manufactured by The Bentley Engineering Company, of Leicester, England, or other knitting machine provided with upper and lower cylinders, having aligned needle grooves, and needles provided with a hook and latch at each end and cam engaging butts to cooperate with the cam mechanism of either cylinder, the needles being capable of being selected and transferred from one cylinder to the other and vice versa, whereby when all the needles are assembled in the lower cylinder the machine may be operated to produce plain knitting, and by transferring selected needles to the upper cylinder any desired type of rib knitting may be produced. The Komet machine, for example, is provided with an auxiliary thread feeding finger at a distance from the feeding throat, and auxiliary knitting cams capable of cooperating with said auxiliary feeding finger which can be employed for incorporating the elastic thread at spaced courses of plain knitting, and locking it at spaced wales in such courses, in several ways, as fully set forth in an application for Letters Patent of the United States, filed by John H. Miller and Frank Evans, on the 5th day of March, 1937, and given Serial Number 129,206.

The invention can also be carried out in many of its forms on the well known Scott and Williams 75 Model H-H knitting machine, which can be op-

erated to knit rib fabric followed by plain knit fabric, but cannot return to rib knitting in the same stocking after being shifted into condition to knit plain fabric. The invention can also be carried out in a similar manner on the Banner 5 rib to toe knitting machine, made by the Hemp-hill Company of Pawtucket, Rhode Island, as well as on other cylinder and dial machines for making complete socks or anklets or tops therefor.

As these machines are on the market and are well known and form no part of my invention, I will not illustrate or describe them further, or in detail.

Referring to the accompanying drawings: 15

Figure 1 represents a sock embodying my invention.

Figure 2 is an enlarged view of the top of the 20 sock shown in Figure 1, partly broken away.

Figure 3 is an enlarged view of the top of a 25 sock showing a modification of my invention.

Figure 4 is a view similar to Figure 3 showing another modification.

Figure 5 is a view of the top portion of a sock 30 showing another modification.

Figure 5^a is a diagrammatic sectional view of the top shown in Figure 5.

Figure 5^b is a view similar to Figure 5^a showing a modified form of welt.

Figure 6 is an enlarged view of the top of a 35 sock showing another modification.

Figure 6^a is a diagrammatic sectional view of Figure 6.

Figure 7 is an enlarged view of the top of a 40 stocking partly broken away showing another 35 modification of my invention.

Figure 8 shows one of the tops, to wit, that 45 shown in Figure 5, folded upon itself.

In Figures 1 and 2 of the drawings, I have illustrated a man's sock embodying my invention. 40 In these figures, 1 represents the top of the sock, the upper portion 2 of which comprises a plurality of plain knit courses having an elastic thread 3 of rubber, Lastex or other suitable material, incorporated in spaced courses of the plain knitting, the said elastic thread being locked into the fabric at certain predetermined and vertically aligned wales in the courses containing the elastic thread as indicated at 4, in Figure 2, and floated as indicated at 5, in Figure 2, in each course between the points at which this interlocking with the fabric occurs, thus forming a tubular fabric which I have heretofore termed rubber incorporated ridged fabric, it being understood that the elastic thread is fed under tension and that the tension of the rubber thread will draw together the fabric between the wales in which the elastic thread is locked into the fabric, not only in the courses in which the rubber thread is present, but also in the intervening courses, thus reducing its diameter substantially to that of the ribbed fabric, and producing throughout the fabric the series of vertical ridges which are indicated at 6, in Figure 2. This fabric can be readily produced as tubular 65 fabric by means of the Komet machine previously referred to, by knitting with all the needles in the lower cylinder as set forth in the application of John H. Miller and Frank Evans, hereinbefore referred to. In the construction of this 70 portion of the top a suitable selvage or welt is provided at the top of the rubber incorporated ridged fabric, and in this instance, the welt indicated at 7 is formed by knitting a plurality of courses of plain knitting which are folded and

stitched as at 8 in a well known manner. In this instance, the remaining portion of the top 1 is formed of rib knitting as indicated at 9 in Figures 1 and 2, and which can be readily knit on the 5 Komet machine, for example, by transferring every other needle of the circular series to the upper cylinder of the machine and feeding the body thread thereto in the normal operation of the machine for producing rib knitting.

10 The resulting top 1 therefore, comprises in this instance, a section of rubber incorporated ridged fabric 2 adjacent to the upper end of the top to which a lower section 9 of rib fabric, preferably 1 x 1 rib is integrally knitted, the entire top will 15 therefore be form fitting while the upper section 2 contains a sufficient number of substantially continuous rows of floats 5 of the rubber or lastex thread to engage the leg of the wearer and hold the leg of the stocking from slipping downward 20 and obviate the use of a garter. It will also be noted that a great saving in the courses of rubber or lastex thread is effected since it only extends through the upper combined form fitting 25 and self-supporting section 2. It will be understood that the spacing of the courses containing the elastic thread as well as the spacing of the wales in which the elastic thread is locked in the fabric in each course may be varied. If the wales in which the elastic thread is interlocked are 30 separated more widely than the width of one wale and the section 8 is knit with 1 x 1 rib, the rubber incorporated ridged fabric might have a tendency to appear a little wider in the undistended condition of the top than the adjoining rib fabric 9. If desired, the tension of the elastic 35 thread may be slightly increased so as to make the diameter of the ridged fabric 2 the same as the diameter of the rib fabric 9, or the tension on the body thread in the rib fabric 9 could be 40 slightly eased for the same purpose.

In Figures 1 and 2, I have shown the leg of the stocking indicated at 10 as composed of 6 x 3 rib and knit integrally with the last course of the 1 x 1 rib of the top 1. This can be readily accomplished on the Komet machine by distributing the needles between the upper and lower cylinders in alternate groups of 6 x 3, respectively. It is to be understood, however, that the leg of the stocking may be formed of other types of rib knitting, or it may be formed of plain knitting. This can be accomplished by a proper distribution of the needles of the Komet machine, for example, between the upper and lower cylinders in the case of the other types of rib knitting or 45 by bringing all of the needles into the lower cylinder and producing plain knitting where a plain knit leg is desired and the entire stocking is knit on one machine as an integral fabric. I also wish it understood that the top may be knit 50 separately from the leg and foot of the stocking and united thereto by stitching or looping, or it may be transferred to the machine which knits the leg and foot of the stocking in the usual and well known manner, and knit integrally therewith. When transferring is necessary it would 55 ordinarily be preferable that the lower courses of the top be formed of 1 x 1 rib fabric, since such rib fabric is more readily transferred.

In Figure 3, I have shown a stocking top 101 provided with alternating sections 102 and 103, of the rubber incorporated ridged fabric containing the elastic threads 103, and rib fabric, respectively, the uppermost section being of the rubber incorporated ridged fabric and the lowermost section 103 being of rib fabric, preferably

1 x 1 rib, to which the leg 110, in this instance of plain knitting, is knit integrally or attached in any usual or preferred manner. The top 101 is shown as provided with a plain knit welt 107 folded and stitched at 108, as previously described 5 with reference to Figures 1 and 2.

Figure 4 shows a top 201 also formed of alternating sections of rubber incorporated ridged fabric 202, and rib fabric 203, terminating at its lower end in a section of ridged fabric 202 to the 10 lower edge of which the stocking leg 210 here shown as of plain knitting, is knit or secured in any desired manner. The top 201 is also shown as provided with the same type of welt 207 of plain knitting, folded and sewed at 208 as previously described, but in this instance, I have shown the welt provided with elastic threads 207a incorporated in certain courses thereof in the same manner in which the elastic threads 203 are incorporated in the ridged sections 202 of the top, 20 or in any other desired manner, and this construction may be employed with this type of welt, if desired.

In Figures 5 and 5a, I have illustrated another modified form of top 301, which can be made on 25 the Komet machine and can also be made on the Scott and Williams Model H-H machine, and the Banner machine, previously referred to. In this instance, the welt 307 is preferably formed as a tubular welt as clearly illustrated in Figure 5a 30 in a well known way and is followed by a plurality of courses of rib knitting, preferably 1 x 1, rib to form a rib section 309 after which a rubber incorporated ridged section 302 is formed containing the elastic threads 303 in the manner previously described and followed by the leg section 310. The leg section 310, if the stocking is knit on the Komet or Banner machine, may be either of plain knitting or rib knitting, as previously described, but if it is knit on the Scott and Williams machine as a continuous integral fabric, the leg 310 would of necessity, be formed of plain knitting, as this machine cannot be restored to condition to knit rib knitting in the same top or 40 sock after it has been adjusted to produce plain knitting. The top shown in Figures 5 and 5a, however, can obviously be formed on either the Komet, or Scott and Williams, or Banner machine, separately from the leg of the stocking and attached thereto in any of the ways previously described. The top shown in Figures 5 and 5a differs from those previously described in that the upper section thereof is of rib knitting, while the lower section is of the plain knit rubber incorporated ridged fabric 302. A satisfactory top, 50 however, can be made in this manner as the entire top will be form fitting and the section 302 will contain a sufficient number of courses including the elastic threads 303 to support the stocking leg without a garter. In some instances, 55 where a tubular welt is employed, it may be provided with one or more strands of elastic thread within the welt, or incorporated in certain of the welt courses thereof, if desired. In Figure 5b, I have shown a welt 307b similar to that shown in Figures 5 and 5a, in which a series of elastic threads 307b are incorporated within the welt to cause the welt to more snugly fit the leg. Obviously, where elastic threads are incorporated in the welt portion of the top, they will have some 60 self-supporting effect and the number of elastic incorporated courses in the plain knit section or sections of the top may be correspondingly reduced, if desired.

In Figures 6 and 6a, I have shown another 75

slightly modified form of top 401 embodying my invention in which sections 402 at the upper and lower ends of the top are of the plain knit rubber incorporated rigid fabric, previously described, containing the elastic threads 403, the central or intervening portion of the top being of rib fabric as indicated at 409. In this instance, instead of a welt, the upper end of the top is provided with a selvage or anti-ravel edge 407 formed by an elastic thread 407^a, extending through the loops of the first course of plain knitting and forming part of the upper section 402. In this case, the rubber thread 407^a will perform the double function of contributing to the form fitting as well as the self-supporting character of the top. The leg 410 may be of plain or flat knit as shown, or it may be of rib knitting, and in either case, the top and leg may be formed separately and united in any of the ways previously described, if this is found desirable.

Figure 7 illustrates another slight modification somewhat similar to that shown in Figures 5 and 6, and which can be knit on either the Komet or Scott and Williams machines, as previously described. In this instance, the stocking top indicated at 501 and broken away, comprises a tubular welt 507, followed by a comparatively short section of rib knitting indicated at 509, the remainder of the top being formed of plain knit rubber incorporated ridged fabric 502, previously described, containing the elastic threads 503, and being of any desired length, and followed by the leg portion 510, which is preferably of plain knit fabric. If, however, this stocking is knit on the Komet machine, the leg may be of rib fabric, if desired, or the top may be formed separately and attached to any type of leg.

It is to be understood that in the production of the plain knit rubber incorporated ridged fabric hereinbefore described, the elastic thread may be locked in the fabric in any desired manner. For example, it can be fed to the hooks of the needles forming the selected wales and knit with the body thread at such wales, or it can be fed below the latches of selected needles, in which case, it will be cast over the tops of said needles and locked in the fabric, or the elastic thread may be fed to the hooks of selected needles which are operated to draw loops of the elastic thread only and cast off the body thread. I further wish it to be understood that I do not claim the herein described plain knit rubber incorporated ridged fabric per se.

While I have described the plain knit or flat fabric as having the elastic thread incorporated in certain courses and locked in the fabric at vertically aligned points so that it will contract the fabric into vertical rib-like ridges, it is to be understood that the elastic thread may, if desired, be locked in the fabric at any desired separated points or wales, in alignment, so that the fabric may be contracted into inclined or spiral ridges, or into small checks, diamonds, or other figures or patterns, in accordance with the ideas of the manufacturer.

It will also be understood that the rib knit sections may also be varied, by knitting small sections of 1 x 1 rib interspersed with small sections of plain or flat knitting by known means to impart decorative effects, such as the well known basket weave, or similar patterns.

It will also be understood that with a top embodying my invention, it can be worn as a single thickness or folded over as preferred. In those cases where the upper portion of the top is of

rib fabric and the lower part is of the elastic incorporated fabric, as shown in Figure 5, for example, it is peculiarly well adapted to be used in this manner, as the 1 x 1 exposed inner face of the rib knit section appears substantially the same as the outer face, and the elastic thread incorporated plain or flat knit portion is left with the float portions on the inner face, to engage the leg of the wearer, and support the leg of the stocking, sock or anklet. I have shown in Figure 10 8, the top illustrated in Figure 5, folded over in this manner.

What I claim and desire to secure by Letters Patent is:

1. A form fitting and self-supporting top for a stocking, provided at its upper end with anti-ravel means, a section adjacent to the upper end of said top consisting of courses of plain knitting, certain courses thereof having an elastic thread incorporated therein under tension, locked into the fabric at certain wales of said courses, and floated on the inner face of the fabric between said wales, and drawing said fabric into rib-like ridges, a following portion of said top being formed of courses of rib knitting.

2. A form fitting and self-supporting top for a stocking, provided at its upper end with anti-ravel means, a section adjacent to the upper end of said top consisting of courses of plain knitting, certain courses thereof having an elastic thread incorporated therein under tension, locked into the fabric at certain wales of said courses, and floated on the inner face of the fabric between said wales, and drawing said fabric into rib-like ridges, a following portion of said top being formed of courses of rib knitting, said anti-ravel means having associated therewith elastic thread, under tension, tending to draw it upon the leg of the wearer.

3. A form fitting and self-supporting stocking top, comprising a tubular portion consisting of a plurality of seamless courses of rib knitting and a tubular portion consisting of a plurality of courses of plain knitting having an elastic thread under tension incorporated in certain of said plain courses, locked into the fabric at certain corresponding wales of said courses and floated on the inner face of the said plain fabric between the wales at which it is so locked, the tension of said elastic thread serving to draw said plain fabric into vertical rib-like ridges, said anti-ravel means at the upper end of said top provided with elastic thread associated therewith under tension and to draw the upper end of the top upon the leg of the wearer.

4. A form fitting and self-supporting top for a stocking provided at the upper edge with an anti-ravel welt, a section immediately below said welt formed by a plurality of rib courses, and a section below said rib section formed by a plurality of plain knit courses, having an elastic thread incorporated in certain courses thereof, under tension, locked into the fabric at certain wales in said courses, floated on the inner face of the fabric between said wales, and drawing the plain knit fabric into rib-like ridges.

5. A form fitting and self-supporting top for a stocking provided at the upper edge with an anti-ravel welt, a section immediately below said welt formed by a plurality of rib courses, and a section below said rib section formed by a plurality of plain knit courses, having an elastic thread incorporated in certain courses thereof, under tension, locked into the fabric at certain wales in said courses, floated on the inner face

of the fabric between said wales, and drawing the plain knit fabric into rib-like ridges, said welt being provided with elastic thread, under tension, for drawing it upon the leg of the wearer.

5 6. A form fitting and self supporting top for a stocking provided at its upper end with anti-ravel means, portions of said top comprising a plurality of consecutive courses of plain knit fabric formed of inelastic body thread, certain courses thereof having an elastic thread incorporated therein under tension united to the fabric at separated points in said courses and floated on the inner face of the fabric between said points, the other portions of said top comprising consecutive courses of rib knitting formed of body thread only and containing the same number of stitches as those of the plain knit fabric.

7. An article of hosiery having a form fitting and self supporting top, provided at its upper end with anti-ravel means, portions of said top comprising a plurality of consecutive courses of plain knit fabric formed of inelastic body thread, certain courses thereof having an elastic thread incorporated therein under tension, united to the fabric at separated points in said courses and floated on the inner face of the fabric between said points, the other portions of said top comprising consecutive courses of rib knitting formed of body thread only and containing the same number of stitches as those of the plain knit fabric, said body thread being continuous throughout the plain knit and rib knit portions of the top, and having a leg portion knit into the last course of the top.

35 8. An article of hosiery having a form fitting and self supporting top, provided at its upper end with anti-ravel means, portions of said top comprising a plurality of consecutive courses of plain knit fabric formed of inelastic body thread, certain courses thereof having an elastic thread incorporated therein under tension, united to the fabric at separated points in said courses and floated on the inner face of the fabric between said points, the other portions of said top comprising consecutive courses of rib knitting formed of body thread only and containing the same

number of stitches as those of the plain knit fabric, said body thread being continuous throughout the plain knit and rib knit portions of the top, and having a leg portion knit into the last course of said top and formed of the same body thread.

9. A form fitting and self supporting top for a stocking, provided at its upper end with anti-ravel means and composed of alternating bands, certain of said bands comprising a plurality of consecutive courses of plain knit fabric formed of inelastic body thread, certain courses thereof having elastic thread incorporated therein under tension, united to the fabric at spaced points in said courses and floated on the inner face of the fabric between said points, the outer of said alternating bands comprising consecutive courses of rib knit fabric formed of the inelastic body thread only and having the same number of stitches as those of the plain knit bands, the tension of the elastic thread drawing the plain knit fabric bands to substantially the same diameter as the rib knit bands and forming vertical ridges in the plain knit bands approximately corresponding with the ribs of the rib knit bands.

10. A form fitting and self supporting stocking top comprising a tubular portion consisting of a plurality of courses of rib knitting and an integral tubular portion consisting of a plurality of courses of plain knitting of substantially the same number as the rib knit courses, each of said plain knit courses having the same number of stitches as the rib knit courses and having an elastic thread under tension incorporated in certain of said plain knit courses, united to the fabric at spaced points in said courses and floated on the inner face of said plain knit fabric between said points, the floated portions of the elastic thread forming horizontal beads on the inner face of the fabric to indent the leg of the wearer and support the said top and the leg of the stocking, whereby the rib knit portion of said top and the anti-ravel means may be turned downward on the exterior of the plain knit portion.

JOHN WYCKOFF METTLER. 45
